(57) **CLAIM**

The ornamental design for an adaptor, as shown and described.

DESCRIPTION

FIG. 1 is a perspective view of the adaptor as viewed from the bottom;

FIG. 2 is a top plan view thereof;

FIG. 3 is a front elevational view thereof;

FIG. 4 is a left side elevational view of the adaptor of FIG. 3;

FIG. 5 is a right side elevational view of the adaptor of FIG. 3;

FIG. 6 is a rear elevational view thereof;

FIG. 7 is a bottom plan view thereof; and,

FIG. 8 is a perspective view similar to FIG. 1, but showing the cover of the adaptor in a closed position.
